AIR REGISTER FOR FURNACES

Filed Nov. 9, 1946

UNITED STATES PATENT OFFICE

2,515,813

AIR REGISTER FOR FURNACES

Hugh Wiant, Westfield, N. J.

Application November 9, 1946, Serial No. 708,954

1 Claim. (Cl. 158—1.5)

1 This invention relates to air registers for furnaces of the type employed in industrial installations wherein relatively large quantities of fuel are burned, and the invention consists essentially of a device inserted through an opening in the furnace wall which is adapted to support the fuel burner and provide means for controlling the flow of combustion supporting air into the furnace.

One of the objects of the present invention is to provide an air register of the above general type and for the specified purposes that may be completely assembled as a unit prior to the installation thereof in a furnace. Such an arrangement greatly facilitates installation of a register and the only operation necessary at the furnace is to attach the register to the supports therefor.

Another object of the invention is to provide an air register which has means for holding the burner to be associated therewith in place at substantially the center of the register and without any appreciable obstruction, other than that of the burner itself, to the flow of combustion supporting air through the register.

Still another object of the invention is to provide a register which effects a more nearly complete mixture of the fuel with the combustion supporting air whereby more complete and rapid combustion is possible. Such an arrangement tends to decrease the flames in the furnace whereby the furnace may have a smaller combustion space.

Still another object of the invention is to provide an air register having a minimum number of parts or components and particularly a minimum number of movable parts whereby adjustment and servicing of the register is facilitated.

The above and further objects of the invention will be more apparent hereinafter in the following detailed description of a preferred embodiment thereof wherein reference is made to the accompanying drawings, in the latter of which:

Fig. 1 is a vertical sectional view taken substantially through the center of an air register constructed in accordance with the present invention;

Fig. 2 is a front end view partly in section of the register shown in Fig. 1;

Fig. 3 is a sectional view taken substantially on line 3—3 of Fig. 1; and

Fig. 4 is a fragmentary detailed view of a part of the front of the register.

Referring to the drawings, the register includes a main cylindrical section or tunnel, indicated generally by reference numeral 11, which is adapted for insertion through an opening of ap-

propriate size in the wall of a furnace. A furnace wall composed of the usual material is indicated by reference numeral 12, and the length of the tunnel 11 is such that with the inner end 5 substantially flush with the inside of the furnace wall, the outer end thereof will extend a considerable distance from the outside of the wall.

The tunnel 11 has formed on the outer end thereof a radially extending flange 13 which is 10 rectangular in shape, and bolts such as 14 extending through the flange enable the tunnel to be secured to a pair of channel members 16. The channel members 16, one above and one below the tunnel 11, may also form a part of the furnace wall supporting structure, and a plurality of registers of the type shown in the drawings may be mounted in spaced relation therealong. Since the entire register of the present invention, as will appear, is secured in place only by the bolts 14, it will be obvious that installation or replacement thereof is a relatively simple and easy operation and which requires no assembling at the furnace.

The outer end of the tunnel 11 is open, and secured thereto by means of cap screws 17, Fig. 25, is a cup-shaped cover, indicated generally by reference numeral 18, which has an end section 19 and a cylindrical section 21 having substantially the same inside diameter as that of the tunnel 11. The cylindrical section 21 of the cover 18 has a plurality of rectangular shaped openings or air ports 22 therein, and the end section 19 has a plurality of openings or ports 23 therein. The end section 19 also has a central opening or bore 24 with a sleeve 26 formed integrally therewith. Among other things, the sleeve 26 provides an opening through which a burner, indicated generally by reference numeral 27, may be inserted in the register. The burner 27 may be of the type disclosed in my co-pending application bearing Serial No. 682,576, filed July 10, 1946.

40 The burner extends into the register so that the tip thereof, as shown in Fig. 1, is a little short of the inner end of the tunnel and it is held in place with respect to the register by set screws such as 28 through the sleeve 26.

45 The end section 19 of the cover 18 extends a slight distance beyond the cylindrical section 21 to form a retaining ridge 30 for a split sleeve 29 surrounding the cylindrical section and located between the ridge and the flange 31 by which the cover is attached to the tunnel 11. The split sleeve 29 has a plurality of rectangular shaped openings or ports therein corresponding to openings 22 in the cylindrical section 21 of the cover. By 50 rotating the sleeve 29 around the cylindrical sec-

tion 21, the area of the openings through both may be increased or decreased to control the amount of combustion supporting air flowing to the burner.

In order that the sleeve 29 have the proper clearance to insure that it can be moved with a minimum of force, an adjustment is provided for slightly increasing or decreasing the size of the sleeve. This adjustment consists of slotted holes such as 32 in a sleeve operating member 34 and screws such as 33 through these slots and other holes in the member 34 into the sleeve to provide means for rigidly connecting the ends of the split sleeve.

The operating member 34 may be connected through a link 36, preferably adjustable, to a suitably guided register operating rod 37. Other similar links, such as 36a, connecting other register operating members, such as 34a, to the rod 37 enable a plurality of registers to be operated simultaneously.

Pivottally mounted on the inner end of the central sleeve 26 of cover 18 is a disc member 38 with openings 39 therein corresponding to the openings 23 in the section 19 of the cover. Threaded into the disc 38 and extending through one of the openings 23 in the cover 18 is a member 41. By unloosening the member 41 the disc 38 may be rotated to bring the openings 39 therein into registry with the openings 23 in the cover, or to an intermediate position as shown in Fig. 4, and thereby provide means for inserting a torch in the register to light the burner and to observe the same.

Located inside the tunnel 11 near the inner end thereof is a ring 42 which, as shown in Fig. 1, slopes inwardly at an angle of approximately 45° toward the central axis of the tunnel 11. Next to the ring 42 and extending to the inner end of the tunnel 11 is a ring of refractory material 43. The inner diameter of the refractory ring 43 is substantially equal to the inner diameter of the ring 42 and the reduction in diameter of the tunnel 11 that is caused by the ring 42 and refractory material 43 increases the velocity of the air passing through the tunnel and directs the same toward the center thereof and toward the tip of the burner 27.

Located on the inner side of the ring 42 in the tunnel 11 are a plurality of angularly positioned fins 44. These fins impart a whirling motion to the air flowing through the tunnel 11 whereby the air is more thoroughly mixed with the fuel projected from the burner tip. In addition to giving the combustion supporting air a whirling motion, the fins being next to the ring 42 and having an edge anchored thereon as by welding are heated by the absorption of heat from the burner flame, and accordingly the air flowing past the fins is partially preheated. The preheating of the air is a material aid to combustion, particularly in the burning of fuel oil. The refractory ring 43, which is also heated by the absorption of heat from the burner flame, tends to heat the ring 42 whereby the fins 44 are heated.

In accordance with the invention it will be obvious that an air register is provided with which a burner may readily be associated in such a manner that greater accelerating action of the burner

is obtained, resulting in the reduction of the space required for combustion. Also, a register is provided which has a minimum number of movable parts which may easily and readily be adjusted and which readily adapt themselves for simultaneous adjustment by a single control member when a plurality of such registers are employed in a furnace.

While the invention has been described and shown in only a preferred embodiment thereof, it will be obvious that various modifications thereof may occur to those skilled in the art without departing from the spirit or essential attributes thereof, and it is desired therefore that only such limitations be placed thereon as are specifically set forth in the appended claim.

What is claimed is:

In combination with a fuel burner, an air register adapted for insertion through an opening in a furnace wall, said register including a cylindrical tunnel section of uniform outer diameter adapted to extend through said furnace wall, said tunnel section having detachably secured to the outer end thereof a cover, said cover including a control means for controlling the amount of combustion supporting air flowable through said register, said control means including a cylindrical section of said cover substantially equal in diameter to that of said tunnel section with a set of openings therein, a pair of radially extending guide flanges formed on the outside of said cylindrical section adjacent the ends of said openings therein, a split cylindrical sleeve having a set of openings corresponding to those in the cylindrical section of said cover, said split sleeve surrounding the cylindrical section of said cover having the openings therein, said sleeve being rotatable about the axis of said cylindrical section and between said guide flanges whereby movement of said sleeve with respect to said cylindrical section is effective to control the air through both of said sets of openings, means for joining the sides of said split cylindrical sleeve to form a rigid sleeve, said last mentioned means being adjustable to vary the diameter of said split sleeve, said cover also including an end section having at its center a sleeve for supporting on the inside thereof the burner tube, openings in said end section, a disc element abutting said end section and rotatable on said sleeve to bring openings therein into and out of registry with those in said end section.

HUGH WIANT.
